Judson et al., U.S. Appl. No. 29/347,611, filed Mar. 12, 2010.

Primary Examiner — Rashida Johnson*(74) Attorney, Agent, or Firm* — Nixon & Vanderhye, P.C.(57) **CLAIM**

The ornamental design for a respiratory mask, as shown and described.

DESCRIPTION

FIG. 1 is a front perspective view showing a respiratory mask according to our new ornamental design;

FIG. 2 is a reverse perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines represent unclaimed structure of the respiratory mask and form no part of the claimed design.
